UNITED STATES PATENT OFFICE.

WALTER SAMS, OF CHICAGO, ILLINOIS.

SAVINGS-BANK.

No. 862,282.

Specification of Letters Patent.

Patented Aug. 6, 1907.

Application filed March 6, 1907. Serial No. 360,840.

To all whom it may concern:

Be it known that I, WALTER SAMS, a citizen of the United States, residing at Chicago, in the county of Cook and State of Illinois, have invented a certain new and useful Improvement in Savings-Banks, of which the following is a full, clear, concise, and exact description, reference being had to the accompanying drawings, forming a part of this specification.

My invention relates to portable savings banks, and 10 is of particular service in the manufacture of pocket size savings banks.

My invention has for its object the very simple construction of a savings bank into which coin may readily be inserted and access to which may be had by simple 15 means.

In practicing my invention, I so construct one of the wall portions that it is changeable in shape, to which end I preferably slit this wall portion and permit the margins of said slit to overlap, this wall portion 20 thus being adjustable with the aid of a tool. The adjustable wall portion is desirably made of sheet metal possessing sufficient resiliency so that when the tool is removed, the said wall portion will resume its original shape to restore the bank to its normal condition.

25 The wall portion of the bank thus modified in structure constitutes a contractible and expansible wall portion. The said wall portion that is thus made changeable in size, is desirably ring-shaped and preferably has separable interlocking engagement with at least one 30 end wall and desirably two end walls, the said end walls preferably having inturned flanges that interlock with the edges of the ring-shaped wall portion, when expanded, the edge portions of the ring-shaped wall being desirably flared for this purpose. The slit in 35 the ring-shaped wall portion desirably extends entirely throughout its length, so that when a suitable tool is applied, such as a spanner clamp, the circular wall portion may be sufficiently contracted to become disengaged from its end walls, whereupon access to 40 the bank may be had. Not only is there an advantage in having the bank thus accessible, but the component parts thereof are readily assembled by means of my improved construction, by the manufacturer as well as the user.

45 I will explain my invention more fully by reference to the accompanying drawing, showing the preferred embodiment thereof, in which—

Figure 1 is a view in elevation of the bank. Fig. 2 is a sectional view on line 2 2 of Fig. 1. Fig. 3 is a sectional view on line 3 3 of Fig. 1. Fig. 4 shows a form 50 of tool that may be employed to collapse the ring-shaped wall.

Like parts are indicated by similar characters of reference throughout the different figures.

There are but three component parts of the bank 55 illustrated, one of which is the ring-shaped wall portion *a*, while the others of which are the disk end walls *b* *c*. The coin passage may be provided in any suitable portion of the bank structure, the coin passage being indicated at *d* in the ring-shaped wall *a*. I have provided a coin channel at *d* which permits the coin readily to be inserted, but prevents it from being readily withdrawn, though I do not wish to be limited to the means employed for the purpose of preventing the withdrawal of coin. The end walls are provided with 60 inturned flanges *e f* that are adapted to receive the flaring edge portions of the wall *a*. The wall *a* is desirably slit, so that it may have overlapping end portions, as indicated at *g*. The tool *h* indicated in Fig. 4, may be encircled about the wall portion *a*, and when contracted by hand pressure, may increase the overlap at *g* until the wall *a* is sufficiently reduced in diameter to permit its disengagement from one or both of the end walls *b* *c*, whereupon the contents of the bank may be removed. The tool *h* has a lug *h*¹ on its inner surface 70 whereby to promote the engagement of said tool with the ring-shaped wall portion *a*.

The portions margining the slit in the wall *a* are desirably overlapped slightly when the bank walls are assembled, so that movement of the portions margining 80 the slit toward each other may at all times be assured. Moreover, by this overlapping feature, no opening need be normally presented there, and, therefore, it is not necessary to extend the end walls to cover said opening. The resiliency of the wall element *a* is sufficiently 85 great so that very positive engagement between said wall portion and the wall portions *b* and *c* is assured, the office of the tool *h* being required in order to overcome this resiliency sufficiently to enable the assembly 90 of the parts *a b c*. To reassemble the parts, the tool *h* is again compressed sufficiently to reduce the diameter of the wall *a* so that it may be engaged at its flaring ends with the insetting flanges *e f*, this engagement of the wall *a* with the end walls *b* and *c* being reeffected 95 when pressure upon the tool *h* is removed.

While I have herein shown and particularly described the preferred embodiment of my invention, I do not wish to be limited to the precise construction shown, but,

Having thus described my invention, I claim as new 100 and desire to secure by Letters-Patent:—

1. A bank structure including an intermediate wall portion, and two end wall portions, said intermediate wall portion being slit along its length, whereby it is made changeable in size throughout, and having separable interlocking engagement at its ends with the end wall portions, the edge portions of the central wall portion being flared 105 outwardly, while the edge portions of the end walls are formed to constitute inturned flanges, whereby the inter-

- locking engagement between the central wall portion and the end wall portions is afforded, the portions margining the slit in the central wall portion overlapping when the bank parts are assembled. 30
- 5 2. A bank structure including an intermediate wall portion, and two end wall portions, said intermediate wall portion being slit along its length, whereby it is made changeable in size throughout, and having separable interlocking engagement at its ends with the end wall portions. 35
- 10 the edge portions of the central wall portion being flared outwardly, while the edge portions of the end walls are formed to constitute inturned flanges, whereby the interlocking engagement between the central wall portion and the end wall portions is afforded.
- 15 3. A bank structure including an intermediate wall portion, and two end wall portions encompassing the intermediate wall portion and interlocking therewith, said intermediate wall portion being slit along its length, whereby it is made contractible in size throughout to release it from engagement with the end wall portions, and having separable interlocking engagement at its ends with the end wall portions, the portions margining the slit in the central wall portion overlapping when the bank parts are assembled. 40
- 20 4. A bank structure including an intermediate wall portion, and two end wall portions encompassing the intermediate wall portion, said intermediate wall portion being slit along its length, whereby it is made contractible in size throughout to release it from engagement with the end wall portions, and having separable interlocking engagement at its ends with the end wall portions, the portions margining the slit in the central wall portion overlapping when the bank parts are assembled. 45
- 25 4. A bank structure including an intermediate wall portion, and two end wall portions encompassing the intermediate wall portion, said intermediate wall portion being slit along its length, whereby it is made contractible in size throughout to release it from engagement with the end wall portions, and having separable interlocking engagement at its ends with the end wall portions, the portions margining the slit in the central wall portion overlapping when the bank parts are assembled. 50

size throughout to release it from engagement with the end wall portions, and having separable interlocking engagement at its ends with the end wall portions. 30

5. A bank structure including a resilient wall portion, and an end wall portion encompassing the resilient wall portion and interlocking therewith, said resilient wall portion being slit, whereby it is made contractible in size to release it from engagement with the end wall portion, the portions margining the slit in the resilient wall portion overlapping when the parts of the bank are assembled. 35

6. A bank structure including a resilient wall portion, and an end wall portion encompassing the resilient wall portion and interlocking therewith, said resilient wall portion being slit, whereby it is made contractible in size to release it from engagement with the end wall portion, the portions margining the slit in the resilient wall portion overlapping when the parts of the bank are assembled, the end wall portion being provided with an insetting flange part, while the resilient wall portion is flanged outwardly so as to be insertible where flanged beneath the flanged part of the end wall portion. 40

In witness whereof, I hereunto subscribe my name this 16th day of February A. D., 1907. 45

WALTER SAMS.
